(57) **CLAIM**

We claim, the ornamental design for a reinforcement arms and collar for an expandable cannula tip, as shown and described.

DESCRIPTION

FIG. 1 is a perspective view of a reinforcement arms and collar for an expandable cannula tip comprising the new design;

FIG. 2 is a side view thereof;

FIG. 3 is an opposing side view thereof;

FIG. 4 is a bottom view thereof; and,

FIG. 5 is a top view thereof.

The broken lines in the drawings illustrate portions of the reinforcement arms and collar for an expandable cannula tip and form no part of the claimed design.
